UNITED STATES PATENT OFFICE.

PAUL F. WOLLENWEBER, OF TOLEDO, OHIO, ASSIGNOR TO ELECTRIC AUTO-LITE CORPORATION, OF TOLEDO, OHIO, A CORPORATION OF DELAWARE.

ELECTRIC SWITCH.

1,398,053.

Specification of Letters Patent. Patented Nov. 22, 1921.

Application filed April 25, 1918. Serial No. 230,712.

To all whom it may concern:

Be it known that I, PAUL F. WOLLENWEBER, a citizen of the United States, residing at Toledo, in the county of Lucas and 5 State of Ohio, have invented certain new and useful Improvements in Electric Switches, of which I declare the following to be a full, clear, and exact description.

This invention relates to electric switches 10 of the longitudinally reciprocating type, and is particularly applicable for use in connection with a heavy current circuit such as is employed in starting internal combustion engines.

15 The principal object of the invention is to provide a switch of the above named type possessing novel means of effecting the "back kick" or release.

Another object is to produce a switch in 20 which full pressure contact is automatically maintained at the electrical terminals until the exact moment of release.

Further objects of this invention relate to economies of manufacture and details of 25 construction as will hereinafter appear from the detailed description to follow. I accomplish the objects of my invention in one instance by the devices and means described in the following specification, but it is evident that the same may be varied widely 30 without departing from the scope of the invention, as pointed out in the appended claims. A structure constituting one embodiment of my invention, which may be 35 the preferred, is illustrated in the accompanying drawings forming a part thereof, in which:

Figure I is a top view of the assembled switch.

40 Fig. II is a plan view of the switch with the top of the casing removed and parts in section.

Fig. III is a sectional elevation of the 45 switch taken on the line III—III of Figs. I, II and IV.

Fig. IV is a sectional elevation on the line IV—IV of Figs. I, II and III.

Fig. V is a view, similar to Fig. IV, showing the parts in operative relation when the 50 plunger is depressed.

Fig. VI is a detail view in side elevation of one member of the locking device, and

Fig. VII is a detail, perspective view of the other member of the locking device.

In the drawings, similar reference numerals refer to similar parts throughout the several views, and the sectional views are taken looking in the direction of the small arrows at the ends of the section lines.

As illustrated, I provide a plunger rod 1 of appropriate length, to the upper end of which is attached an operating button 2 by a rivet 3. Below the middle of the rod, a notch 4 is made in the rod, the lower edge of which forms a cam surface 5 and the upper edge 6, an abrupt laterally projecting wall. Just above this notch a pin 7 is inserted through the plunger. The ends of the pin project beyond the plunger surface for a purpose hereinafter described.

The plunger is adapted to have axial movement in a short cylindrical sleeve 8, shown in detail in Fig. VI. The lower half of the cylinder is squared on three sides, (as best shown in Fig. II) the axial center of 75 the squared portion being offset from the cylinder axis to such an extent that the center plane surface 9 is nearest the cylinder axis and a vertical slot 10 is cut in the said surface.

A groove 11 is made in the upper end of the plane surface 9 and the cylinder immediately above the groove is cut to form a slanting plane face 12 (Fig. VI). Another groove or slot 13 is cut axially in the upper 85 cylindrical portion of the sleeve, the plane of the slot lying parallel to the center plane surface 9. When assembled, the plunger has sliding movement in the cylinder, with the ends of the projecting pin lying in the 90 groove 13. When the pin lies at the base of the groove, the upper wall 6 of the notch in the plunger is parallel with the upper wall of the groove 11, as shown in Fig. V.

The means for holding the switch in contact position comprises a plate 14 with an elongated aperture 15 in which the squared portion of the sleeve 8 is adapted to slide. Integral with the ends of this plate are outwardly extending projections 16 and 17 100 which have bearing in the walls of the casing 27. A compressed spring 18 is coiled about the projection 17 of the plate and tends to move the plate against the plane surface 9, so that, when the plate registers 105 with the groove 11, it moves into the groove, locking the sleeve in place and resting in the cut-out portion 4 of the plunger adja-

cent the upper wall thereof. The cut away portion 12 permits easy insertion of the plate in the notch.

Electrical contact in the switch is made

5 by means of a strip 19 of sheet copper, having a central aperture 20 (Fig. III) through which the plunger 1 projects, and the strip 19 is insulated from the sleeve 8 by means of a strip of insulation fiber 21.

10 The end of the plunger slides in a hollow cylinder 22, closed at its lower end, and having an outwardly extending flange 23 at its upper end. A strip of non-conducting fiber 24 insulates the flange 23 from the contact plate 19.

15 The end cylinder 22 has vertical movement in the base of the casing 27. Terminal electrodes 25 and 26 are attached to the base of the casing 27, which, in the present form 20 of my invention, consists in a narrow box of sheet metal to which a lid or top 28 with a cup stamping 29, integrally formed, is attached. The plunger passes through an aperture formed centrally in the base of the 25 cup 29 and is held in normal position by means of an encircling spring 30 and by means of the pin 7. Similarly, the end cylinder 22 is held in elevated normal position on the base by means of a coil spring 31, 30 compressed between the flange 23 of the cylinder and the base of casing.

25 The terminal contacts 25 and 26 take the form of bolts having flattened heads 32 and screw ends 33 with nuts 34 adapted to hold 35 the bolts in position on the casing, and the connectors 35, in close contact with the bolts. The bolts are insulated from the casing by means of the insulation lining 36 and the insulation washers 37 and 38.

40 The operation of the switch will now be described. During the initial downward movement of the plunger rod against the compression spring 30, the pin 7 moves freely in the slot 13 of the sleeve 8 until it 45 rests at its bottom. Movement is then imparted to the contact plate 19, through the sleeve, against resistance of the compression spring 31. At the point of complete contact of the plate with terminal bolts 25 and 26,

50 the sliding bar moves into the groove 11 on the sleeve and seats in the notch 4 in the plunger rod 1, and uniform compression is thus maintained at the extreme downward position of the plunger. When the pressure

55 on the rod head 2 is removed, the rod begins an upward movement through expansion of the spring 30 and, due to the vertical portion of the notch 4 in the rod 1, the locking bar 14, compressed by its spring 18, remains seated in the sleeve slot 11, until the lower inclined end of the notch moves the bar out of the groove 11, when the spring 31 exerts

60 its full force to separate the contact surfaces and effect a clean, quick break.

The switch above described is especially

advantageous for heavy current duty, where low resistance and non-arching characteristics are required.

I am aware that the particular embodiment of my invention, herein shown and described, 70 is susceptible of considerable variation without departing from the spirit of my invention, and, therefore, I desire to claim the same broadly, as well as specifically, as indicated by the appended claims.

Having thus described my invention, what I claim as new and desire to secure by Letters Patent, is:

1. In an electric switch, the combination 80 of a casing, having a pair of contacts secured thereto, a rod slidable in said casing, a sleeve loosely mounted on said rod, a member carried by said sleeve and adapted in one position to bridge said contacts, a spring tending to hold said member away from said 85 contacts, latching means carried by said casing for holding said sleeve against movement in either direction and means on said rod for releasing said latching means when the rod is moved to a predetermined position.

2. In an electric switch, the combination 90 of a casing having a pair of contacts secured thereto, an operating rod slidable in said casing, a sleeve adapted to have limited sliding movement on said rod, a member carried by said sleeve for bridging said contacts when said rod is depressed and a latch for holding said bridging member in contact position, said sleeve and said rod having recesses positioned to be brought into alignment to receive said latch, the recess on said rod having a cam portion to engage and move said latch out of holding position when the rod is moved to release position. 105

3. In an electric switch, the combination 110 of a casing; a plurality of binding post terminals in said casing and insulated therefrom; a contact bar adapted to bridge said terminals; an actuating plunger movable axially through said casing; resilient means tending to resist motion of said plunger; a pin extending through the plunger; a sleeve movable on the plunger, having a slot in which the pin is adapted to move; a hollow 115 cylinder slidable through the base of said casing, in which the plunger has slidable movement and resilient means tending to resist movement of said cylinder.

4. In an electric switch, the combination of 120 a casing; a plurality of binding post terminals in said casing and insulated therefrom; a contact bar adapted to bridge said terminals; a plunger rod movable in said casing; resilient means tending to resist movement of the plunger rod; a pin extending through said plunger rod; a notch cut in said plunger rod having a lower cam edge; a sleeve slidable on the plunger rod having its upper end slotted to receive the 130

pin and its lower end squared; a transverse groove in the squared portion of the cylinder; a locking bar having a transverse portion adapted to seat in said transverse groove when in locking position; resilient means tending to force said bar into the transverse groove; a hollow cylinder slideable through the base of the casing, forming a support for the contact bar; and resilient means tending to force the cylinder into the casing.

5. In an electric switch, the combination of a stationary contact, a movable contact, a sleeve engaging said movable contact and having a groove, a plunger rod projecting through said sleeve, having a notch with a cam surface and adapted to move said sleeve for the purpose of moving said movable contact into engagement with said stationary 15 contact, and a locking device movable into locking engagement with said groove and movable out of said groove by said cam

surface after the plunger rod has been moved relative to said sleeve to effect a clean, quick break between the contacts. 25

6. In an electric switch, the combination of stationary contact means, movable contact means, a locking device, actuating means for the movable contact, means comprising a movable member having a groove 30 and a second movable member having a notch with a cam surface, the second member being adapted to move the first member in one direction so that the groove and notch are brought into coöperative relation with 35 the locking device at the same time and the second member being adapted to initially move in the reverse direction relative to said first member whereby said cam surface moves the locking device out of said groove. 40

In testimony whereof, I affix my signature.

PAUL F. WOLLENWEBER.
